CHARLES E. SMITH, OF SAGINAW, MICHIGAN, ASSIGNOR OF ONE-FOURTH TO GUSTAVE R. MEYER, OF SAGINAW, MICHIGAN.

ROLL FOR BEAN-PICKING MACHINES.

1,072,665.

Specification of Letters Patent.

Patented Sept. 9, 1913.

Application filed November 1, 1912. Serial No. 729,124.

To all whom it may concern:

Be it known that I, CHARLES E. SMITH, a citizen of the United States, residing at Saginaw, in the county of Saginaw and 5 State of Michigan, have invented certain new and useful Improvements in Rolls for Bean-Picking Machines; and I do hereby declare the following to be a full, clear, and exact description of the invention, such as 10 will enable others skilled in the art to which it appertains to make and use the same.

This invention is a roll for bean picking machines and relates more particularly to rolls of the type that are commonly used in 15 that class of bean picking machines in which rolls are arranged in pairs with their axes parallel and inclined from the horizontal so that the upper peripheries of the rolls of a pair form a downwardly inclined 20 groove along which the beans to be picked are allowed to roll, the supply being fed to the rolls at their upper ends. The rolls are usually provided with intermeshing gears at the upper ends of their shafts and are 25 rotated positively by means of these gears in opposite directions, so that the upper peripheries of the rolls of a pair run toward each other. As the beans move down the 30 groove formed by the two rolls, split or rough beans are drawn through the rolls, while smooth beans pass down the groove and drop off at the lower ends of the rolls.

My improvement relates more particularly to the construction of rolls adapted 35 for such service as above described, and the invention provides means for securing the required degree of hardness of the outer surface of the roll, while still permitting a considerable capacity for yielding to accommodate the split or rough beans that pass 40 between the rolls.

I have found in practice that solid rubber rolls wear rapidly, especially at their upper ends near the place at which the beans are 45 fed to the rolls, and are liable to crush a considerable percentage of the beans, especially if the beans are very dry and brittle. My invention provides a roll of such construction that it not only has the proper degree of surface hardness, but also has the 50 required capacity for yielding, to prevent splitting the beans, and it can furthermore quickly be removed from the shaft, turned end for end and replaced on the shaft.

With these and certain other objects in view, which will appear later in the specifications, my invention consists in the devices described and claimed and the equivalents thereof.

In the accompanying drawings, Figure 1 60 is a longitudinal section of a roll embodying my improvement; Fig. 2 is a transverse section on the line $z-z$ of Fig. 1; Fig. 3 is a face view of one of the end members 65 by which the roll is held in place on the shaft; Fig. 4 is a side view of the same.

As is clearly shown in the drawings, the roll consists in a shell 1 of molded rubber or other suitable material, the shell being formed with longitudinally disposed ribs 2 70 that extend radially inward, their inner ends being adapted to receive the shaft 3, which is inserted by sliding it endwise into the roll. The ribs 2 are preferably thicker at their outer ends and merge into the material of the shell, as shown in Fig. 2, although the configuration of the cross-section may be varied from the form here shown if desired, it being only essential that suitable 75 inwardly projecting ribs shall be secured 80 to the shell, their inner ends adapted to slidingly receive the shaft 3.

The end members by which the ends of the roll are removably secured to the shaft consist in a collar 4 having a set screw 5 or 85 other suitable fastening means by which the collar may be fastened to the shaft 3, one end face of the collar being provided with projecting lugs 6 adapted to be received in the spaces between the ribs 2. The end 90 members preferably close the ends of the rolls and also reinforce them and hold them in place, although the shape of the lugs may or may not be such as to entirely close the space.

While I prefer to mold the shell 1 and the ribs 2 integral, making them both from one grade of material, it will be understood that the outer part of the roll may, if desired, be made of rubber of greater hardness 100 than that of the ribs, but formed integral with them, without departing from the spirit of my invention.

Rolls constructed in accordance with my invention have the required degree of surface hardness to properly pick the beans, yet have sufficient resilience to prevent crushing brittle beans, the resilience being imparted

by the yield of the radial ribs 2 and of the relatively thin parts of the shell between the ribs. This yielding of the roll reduces the power required to drive the rolls, and reduces the friction and wear on the roll-shaft bearings, and prolongs the life of the roll. When the upper ends of the rolls become worn, the rolls may be quickly slipped off their shafts, turned end for end, and replaced on the shafts, thereby aiding in prolonging the life of the rolls.

Having described my invention, what I claim and desire to secure by Letters Patent, is:—

- 15 1. In a roll of the class described, the combination with a shaft, of an outer shell of relatively hard resilient material, a plurality of longitudinally disposed ribs of softer material, each of said ribs extending lengthwise the shaft and having a thickened outer edge formed to merge into the material of the shell, said ribs extending radially inward from said shell and formed integral therewith, the inner ends of adjacent ribs being unconnected and spaced apart and

adapted to slidably engage said shaft on their inner ends, for the purposes set forth.

2. In a roll of the class described, the combination with a shaft, of an outer shell of relatively hard resilient material, a plurality of longitudinally disposed ribs of softer material, said ribs formed with thickened outer edges and shaped to merge into the material of the shell, said ribs extending radially inward from said shell and formed integral therewith, the inner ends of said ribs being spaced apart and adapted to slidably receive said shaft, together with a pair of end members, each comprising a collar received on said shaft, lugs projecting from said collar and received in the spaces between said ribs, and means for removably securing said collar to said shaft.

In testimony whereof, I affix my signature in presence of two witnesses.

CHARLES E. SMITH.
